ICE-MAKING MACHINE

Francis M. Raver, York, Pa., assignor to Flakice Corporation, Brooklyn, N. Y., a corporation of Delaware

Application December 11, 1950, Serial No. 200,155

9 Claims. (Cl. 62—107)

This invention relates to ice making, and more in particular to improvements in the continuous making of ice in the form of thin curved sheets or ribbons where the pieces are of irregular shape and size but of uniform thickness and curvature.

An object of this invention is to provide extremely efficient and dependable apparatus of high capacity which will produce ice of uniform and superior quality. A further object is to provide apparatus which is sturdy and simple in construction, and is adaptable to various conditions of use and to manufacture on a somewhat mass production basis.

The present invention relates to those disclosed in Patent No. 2,310,468 to Short and Patent No. 2,344,922 to Raver; and an important object of the present invention is to provide improved apparatus of the character disclosed in those patents.

The above and other objects will be in part obvious and in part pointed out below.

In the drawings:

Figure 1 is a somewhat schematic showing of one embodiment of the invention with some parts shown in perspective and having portions broken away to show the construction;

Figure 2 is a vertical section of the ice-making unit of the embodiment of Figure 1; and

Figure 3 is a sectional view on the line 3—3 of Figure 2.

In the above-mentioned patent to Raver, an ice-making machine is disclosed wherein a rotating cylindrical evaporator has ice frozen on its outer surface in the form of a thin sheet or ribbon. The ice is removed by an ice-removing unit which has a number of helical wedges rotatably mounted and adapted to move against the ice and effect wedge it from the freezing surface. The cylindrical evaporator is partially immersed in a tank of water and the ice-removing unit is positioned in the top of the tank so as to engage the portion of the freezing surface which is above the surface of the water. With such a machine ice of extremely high quality is produced in an efficient and dependable manner, and commercial machines of that character have enjoyed considerable success.

The illustrative embodiment of the present invention is a commercial machine similar to those just referred to but differs therefrom in certain important respects. Specifically, the present illustrative embodiment is of greater capacity and in actual construction is of much larger size. Furthermore, the present machine is not immersed in a body of water but water is circulated over its freezing surface with the flow being in excess of that frozen. The water which is not frozen returns to a sump tank to which additional water is added and from which the water being circulated is pumped. This construction gives improved heat transfer and permits elimination of the conventional stuffing box.

The construction of the cylindrical evaporator is also different from that shown in the above-mentioned Raver patent. For example, in the Raver patent the cylindrical evaporator is of the "series flow" type with the refrigerant flowing through a helical passageway along the inside of the freezing surface; whereas, in the present machine, the entire space inside the cylindrical evaporator forms the evaporator chamber. Applicant removes the oil film generally encountered in this type of apparatus by washing it off with the refrigerant which is sprayed against the inside surface of the cylindrical evaporator wall with a relatively large portion of it not being evap-

2

orated but remaining a liquid and collecting in the bottom of the evaporator chamber along with the washed off oil. This eliminates the necessity of taking the penalty of low heat transfer due to the oil film or using a mechanical scraper of some type to remove the oil film. The oil along with the liquid and gaseous refrigerant in the bottom of the evaporator chamber is withdrawn constantly to minimize the tendency for the oil to be picked up by the drum as it rotates. The oil consequently does not settle out as a pool as would happen in a dry system, i. e., complete evaporation of the refrigerant. This liquid is withdrawn to a refrigerant surge drum together with the gas refrigerant, and oil and the liquid refrigerant is pumped from this surge drum back into the evaporator again, whereas the gas refrigerant passes to a compressor and is compressed, and the oil is returned to the compressor.

Referring particularly to Figure 1 of the drawings wherein certain of the components of the machine are shown schematically, the ice-making unit 2 is housed in a casing 4 which is broken away to show the ice-making structure and there is a supporting frame 6. Water to be frozen is contained in a tank 8 and is pumped therefrom by a pump 10 driven by motor 12. The refrigerant is illustratively ammonia and a body of liquid ammonia is contained in an insulated surge drum 14 from which it is pumped by an ammonia pump unit 16 to the cylindrical evaporator referred to above. Gas refrigerant is withdrawn from the top of the surge drum and compressed by a compressor 18 driven by motor 20 and the refrigerant is condensed in a condenser 22 and returned in the liquid phase to the surge drum.

Referring again to the left-hand portion of Figure 2, the ice-making unit 2 includes a rotating cylindrical evaporator 24 which is mounted at its ends in a manner to be described below and is rotated about a horizontal axis. Water to be frozen is supplied to the cylindrical freezing surface of drum 24 by a pair of parallel spray pipes 26 and 28 which are connected through pipes as shown to pump 10 and are mounted on the end walls of casing 4. Spray pipe 28 is adjustably mounted relative to the drum freezing surface so that the quality of the ice may be controlled. For example, when it is desirable to have wet ice, the spray pipe is adjusted closer to the ice remover and conversely when relatively dry ice is desired, the spray pipe is adjusted further away from the ice remover so as to allow the ice to be slightly subcooled before it leaves the machine. An ice removing unit 30 is mounted at its ends in a pair of bearings 32 which are rigidly supported on the frame of the machine and permit the ice-removing unit to rotate freely. The ice-removing unit consists of a 5" diameter double-extra-heavy pipe 34 to which fourteen helical or spiral wedges or blades 36 are welded. The ice-removing unit is so mounted that the blades move to within a few thousandths of an inch of the freezing surface of drum 24 but they do not touch the surface. Thus, during operation ice which is formed on the drum is engaged by the blades and this engagement rotates the ice-removing unit while the blades wedge the ice free in a manner to be discussed below.

As indicated above, water to be frozen is pumped from tank 8 to the spray pipes 26 and 28. These pipes are perforated along zones adjacent the freezing surface so that streams of water are projected downwardly from the spray pipes onto the freezing surface and the freezing surface is therefore covered with sheets of flowing water along its sides beneath these pipes. Water is supplied to the freezing surface in excess of the rate at which it freezes so that water flows from the bottom of the freezing surface. The bottom of casing 4 forms a trough which collects this excess water and it is returned through a pipe 38 to tank 8 which acts as a sump tank.

As previously stated, the refrigerant is circulated through the evaporator from the surge tank and the circulation is effected by a pump 16 which withdraws the liquid refrigerant from the surge tank through a pipe 39 and supplies it under pressure through a pipe 40 to a refrigerant inlet pipe 42 at the end of the evaporator. During operation oil passed to the evaporator in the liquid refrigerant, and the gas refrigerant is withdrawn through a pipe 44 and carries with it the unevaporated refrigerant

and the oil. The end of pipe 39 extends above the bottom wall of the surge tank so that only liquid refrigerant flows into it and the oil is collected in a tank 43 and is returned to the compressor.

Referring now to Figure 2 wherein the details of construction of the ice-making unit 2 are shown, drum 24 has a rigid cylindrical wall 45 the outer surface of which forms the freezing surface and the ends of which are closed by end bells 46 and 48. Each of the end bells is dished inwardly and has an extended cylindrical peripheral flange which is welded to the adjacent edge of the wall 45. This construction prevents formation of ice on the extreme edges of the drum shell and is advantageous in that it provides a lighter, more compact and rugged structure than either a straight or outwardly dished end bell without undesirable reduction in ice making capacity. End bell 46 has welded to its center a supporting stud shaft 50 which projects through a mounting bearing assembly 52 and has keyed to its left-hand end a driving sprocket wheel 54. Sprocket wheel 54 is connected through a sprocket chain 56 to a driving sprocket 58 which is rotated by a motor 60 through a gear reduction mechanism 61.

The right-hand end bell 48 has a central opening within which is welded a cylinder 62 together with a reinforcing ring 64, and the right-hand end of this cylinder 62 is welded to a rim or ring 66. Ring 66 in turn has clamped to it a shaft-mounting plate 68 which has a central opening in which is welded a hollowed shaft 70. Shaft 70 extends to the right through a supporting bearing assembly 72 and provides support for the right-hand end of the cylindrical evaporator.

Projecting through shaft 70 is a stationary refrigerant outlet pipe 74 which terminates at the right in a stationary connecting bracket 76 and carries at the left a header 78 in which is mounted a refrigerant pipe 80. Pipe 80 projects downwardly to adjacent the bottom of the evaporator chamber and has its opening lower end so positioned that liquid in the bottom of the evaporator chamber is entrained in the refrigerant gas passing upwardly through pipe 80. Thus, the liquid refrigerant which collects in the bottom of the evaporator chamber and the oil are withdrawn from the evaporator chamber by the outgoing refrigerant gas.

The stationary connecting bracket 76 is provided with an axial refrigerant inlet opening 82 to which the refrigerant supply pipe 40 is connected; and, projecting to the left from this bracket 76 is a refrigerant supply pipe 84. Pipe 84 extends through an opening in header 78, which assists in supporting the pipe. Pipe 84 extends to the left with its left-hand end closed and terminating adjacent the inner surface of bell 46. The joint between pipe 84 and header 78 is substantially gas tight which would not be possible with the conventional spray nozzles. Pipe 84 is provided with a large number of pairs of perforations 86 which project the refrigerant in transverse spray patterns outwardly against the inner surface of the cylindrical evaporator wall 95. These refrigerant outlet openings 86 are of such size, number and relative positions that the individual sprays of each pair impinge on each other to give an atomizing effect such that the entire inner surface of shell 45 is constantly covered by a fine spray of refrigerant. Thus, flash evaporation occurs and the entire drum is cooled at an even rate.

During the ice-making operation the freezing surface is refrigerated and supplied with water to be frozen in the manner outlined above. The ice is then removed from the freezing surface in accordance with the principles of operation of the machines of the character referred to above which embody the invention covered in the above-identified patent to Raver. Referring to Figure 3, after the ice is severed from the freezing surface, it is carried away to the right by a doctor blade 88. Doctor blade 88 is mounted on brackets 90 and has a right-hand portion 92 down which the ice slides after moving to the right across the top of the doctor blade proper. The bracket 90 extends the full length of the machine and with the pivot point 96 and adjusting screws 98 allows multiple, independent, and localized adjustment of the doctor blade so proper clearance may be maintained the full length of the drum. The doctor blade is provided with relatively low temperature resistance heaters 94 which maintain the doctor blade at an elevated temperature. This temperature is such that the ice does not freeze to the doctor blade and yet there is no objectionable heating of the ice.

As many possible embodiments may be made of the

above invention and as many changes might be made in the embodiment above set forth, it is to be understood that all matter hereinbefore set forth, or shown in the accompanying drawing, is to be interpreted as illustrative and not in a limiting sense.

I claim:

1. In ice-making apparatus of the character described, the combination of, a rotatable evaporator having an exterior cylindrical freezing surface upon which ice is formed, water sprayer means to supply water to said freezing surface, means to recirculate water which falls over the freezing surface and remains unfrozen, an ice-removing unit comprising a freely rotatable member having rigid wedging blades which are adapted to move into close proximity to said freezing surface and to wedge ice free therefrom, means pivotally mounting said scraper blade and a plurality of adjusting screws providing multiple and independent clearance adjustment, a scraper blade assembly including a blade portion and heater means to elevate the temperature of said blade portion, and refrigerant distributor means to refrigerate said freezing surface including a centrally positioned sprayer adapted to spray refrigerant against the inside surface of said evaporator throughout the zone of said freezing surface and means to withdraw and recirculate the unevaporated refrigerant.
2. In ice-making apparatus of the character described, the combination of, a cylindrical evaporator having an internal evaporator surface and an external ice freezing surface, means for mounting said evaporator, means to circulate refrigerant through said cylindrical evaporator at a rate in excess of the rate of evaporation of the refrigerant, refrigerant distributor means to refrigerate said surface including sprayer means adapted to spray refrigerant against the inside surface of said evaporator throughout the zone of said freezing surface, refrigerant discharge means to withdraw refrigerant from adjacent the lowest point of said internal evaporator surface to continuously withdraw the unevaporated refrigerant and oil together with the evaporated refrigerant, whereby said internal evaporator is maintained substantially liquid free.
3. Ice-making apparatus as described in claim 2 which includes, water sprayer means to supply water to said freezing surface, and means to recirculate water which falls over the freezing surface and remains unfrozen.
4. Apparatus as described in claim 3 which includes, a scraper blade assembly positioned adjacent said freezing surface and adapted to divert ice from said surface after it is freed by said ice-removing unit, said scraper blade assembly including a blade portion and heater means to elevate the temperature of said blade portion.
5. Apparatus as described in claim 2 which includes, a refrigerant discharge assembly within said cylindrical evaporator and including a fixed header and a pipe extending from said fixed header to closely adjacent the bottom of said evaporator.
6. In ice-making apparatus of the character described, the combination of, a rotatable evaporator having an exterior cylindrical freezing surface upon which ice is formed, an ice-removing unit comprising a freely rotatable member having rigid wedging blades which are adapted to move during rotation to and from close proximity to said freezing surface and to wedge ice free therefrom, refrigerant distributor means to refrigerate said freezing surface including centrally positioned sprayer means adapted to spray refrigerant against the inside surface of said evaporator throughout the zone of said freezing surface, bearing means mounting said rotatable evaporator with its rotary axis so that oil and excess liquid refrigerant may be removed from a liquid zone at one end thereof, and a discharge pipe having an open end in said liquid zone, positioned to continuously withdraw the collected oil and excess liquid refrigerant.
7. An ice-making apparatus as described in claim 6 wherein said sprayer includes, a pipe extending along the axis of said cylindrical freezing surface and having a plurality of pairs of holes each oriented to project the refrigerant against the inner surface of said evaporator.
8. An ice-making apparatus as described in claim 7 wherein said pairs of holes are disposed to impinge the individual spray streams of each pair against each other to produce an atomizing effect whereby the interior sur-

face of said evaporator is covered with a very fine spray and flash evaporation occurs.

9. In the art of making ice or the like, the steps of, spraying liquid refrigerant at a rate substantially in excess of the rate of evaporation into an evaporating chamber and against the internal surface of a cylindrical evaporating zone thereby to refrigerate said zone and also to wash oil from said zone, withdrawing and recirculating the unevaporated refrigerant, continuously withdrawing from said evaporator the oil washed from said refrigerating zone, said withdrawal of said unevaporated refrigerant and said oil being substantially simultaneous and at a zone closely adjacent the bottom of said evaporating chamber to maintain said evaporating chamber substantially liquid free, and spraying water at a rate substantially in excess of the rate of freezing over the exterior of said evaporating zone. 15
